PNEUMATIC PISTON PUMP, DIFFERENTIAL
TYPE

Alexander Boynton, San Antonio, Tex.

Application January 31, 1939, Serial No. 253,880

9 Claims. (Cl. 103—232)

My invention relates to improvements in means for lifting liquids from wells by utilizing the expansive force of gaseous fluids to automatically expel slugs of liquids successively without allowing the pressure fluid to contact the producing formations of the well.

The invention relates to the subject matter of my copending applications Serial Nos. 253,875, 253,876 and 253,877 filed of even date herewith.

By this means slugs of varying lengths may be expelled by simply varying the value of the pressure fluid used to expel them. The slugs may thus be of such length as the well will produce to accomplish any desired rate of production obtainable within the capacity of the well.

To attain the foregoing, and other related objects, the invention utilizes a well casing within which is secured a tube for pressure fluid, internal of which a third tube is used as an eduction means. A hermetic seal is provided between the well casing and the pressure tube, proximate the ground surface, and another hermetic seal is provided between the pressure tube and the eduction tube, the second seal being somewhat above the first. A means is provided for conducting the well formation gas, which accumulates in the annular space between the well casing and the pressure tubing, away from the well through an opening in the casing head. A means is also provided for inducing air or gas into the pressure tube proximate its upper end.

A seal is provided between the pressure tube and the eduction tube proximate their lower ends. A valve to prevent well liquid from entering the pressure tube, when the eduction tube is not in place, is also provided.

None of the foregoing parts or any combination of them are claimed as new, but they are mentioned because their use is essential in combination with a valve to admit well liquid into the eduction tube when pressure fluid to flow the well is available within the pressure tube, and to cut off the entrance of such liquid into the eduction tube when such pressure is not so available.

In the preferred form of the invention a weight or spring is provided to hold said valve normally closed against the admission of well liquid into the eduction tube, and to provide proper difference between the weight of the slug and the force used to expel it. A second valve, acting in unison with the first valve, prevents pressure fluid from escaping through the eduction tube while the first valve is admitting the slug into the eduction tube. The weight that normally holds the first

5 (liquid intake) valve closed also acts to hold the second (air or gas intake) valve open until the slug is expelled. In the preferred form of the invention, a third valve is utilized to hasten the action of the second valve in closing, and attached to said third valve is a fourth valve which acts as a check valve to prevent the escape of well liquid into the pressure tubing at times when there may be no pressure fluid in the pressure tube.

In the other form of the invention, all of the above referred to parts are employed except the third valve which is dispensed with, and a spring is used instead of a weight to urge the movable assembly of valves downward.

I attain the foregoing objects by mechanisms illustrated in the accompanying drawings, in which—

Fig. 1 is a vertical section of a well equipped with this invention.

Fig. 2 is mainly a vertical section of the device showing the liquid intake valve closed, and all other valves open, except the two check valves which are closed.

Fig. 3 is mainly a vertical section of all except the lower portion of the device shown in Fig. 2, showing the liquid intake valve open and all other valves closed, except the check valve which is open, all valves being shown in elevation.

30 Fig. 4 is a vertical section of a modified form of the device shown in Figs. 2 and 3, the upper check valve being shown in elevation.

Fig. 5 is mainly a vertical section of the device shown in Fig. 4, some parts being shown in elevation.

Fig. 6 is a horizontal section on the line 6—6, Fig. 3.

Fig. 7 is a horizontal section on the line 7—7, Figs. 2 and 4.

40 Fig. 8 is a horizontal section on the line 8—8, Figs. 2 and 3.

Fig. 9 is a horizontal section on the line 9—9, Fig. 4.

Fig. 10 is a horizontal section on the line 10—10, 45 Figs. 2, 4 and 5.

Identical characters refer to similar parts throughout the several views.

With reference to the invention as shown in Fig. 2, pressure fluid intake nipple 31 is the 50 foundation member, so to speak, of the device. Seal carrier nipple 25, having check valve seat member 33 pressed or otherwise secured in its upper end, is threadedly engaged upon the lower end of check valve housing nipple 22, which is threadedly engaged upon the lower end of intake

nipple 31. Threadedly engaged with the upper end of pressure fluid intake nipple 31 is valve housing nipple 30, which in turn is threaded upon the lower end of valve sleeve nipple 29, the upper end of which is similarly engaged with weight housing nipple 28, completing the outside shell of the device.

Spacer nipple 33 is threadedly joined to the tubular extension 31c and to sleeve valve shell 40, the latter having radial extensions 40a closely fitted within nipple 30 in order to provide true alignment between members 40 and 29 so that valve member 34 will move truly and not bind in its contact with said members.

Valve lifter piston 35, having legs 35a, that normally land upon the upper end of extension 31c, has its upper end threadedly joined to valve member 34.

Weight 41, having radial guide fins 41a, holds the upper end central and freely movable within nipple 28. A lower finned portion 41b holds the lower end of weight 41 central and freely movable within the central bore through nipple 29. A further and more exact central alignment of fins 41b is provided by the pointed lower end of this finned member resting within the cupped upper extension 34k of member 34.

It will be noted that upper shell valve 34a and lower guide shell 34b are separated by an opening 34d, which opening registers with the opening 40' between members 29 and 40 when valve 34 engages upon its seat 40c, and that ribs 34c join upper and lower portions 34a, 34b, and valve 34 together. The openings 34m between the fins (Fig. 7) are of sufficient aggregate capacity to allow ample pressure fluid for expelling the slugs to pass through them.

Within the valve lifter piston 35, there is a chamber 35d, proximate the lower end of which is an internal circular shoulder 35c which supports the enlarged upper end 36b' of fins 36b which integrally join the enlarged portion 36a of air or gas valve 36 to the tubular lower end 36c. The lower enlargement 36b' of the fins, having an easy working fit within the central bore in extension 31c, is provided as a guide to cause valve 36 to seat truly upon its seat 34h within the central opening in threaded lower extension 34g. The upper enlarged portion 36b' of the fins has slight clearance within the chamber 35d, thus providing an upper guide to hold valve 36 in position to land centrally of its seat.

Within the tubular lower end 36c, a split bushing 37, having a central opening somewhat smaller than the head 38a, is pressed in or welded as shown at 36e to lift check valve 38 when valve 36 rises. Check valve 38 is free to seat upon seat 31e to close passage 31b as shown in Fig. 2, whenever the movable assembly of valves is in the lower position, some clearance being then provided between head 38a and split bushing 37.

Passage 36d communicates between chamber 36c' and the spaces 34m between the fins immediately above tubular end 36c for the purpose of providing for fluid passage around the head 38a.

Radial openings 34f communicate with vertical passage 34j above valve seat 34h in order to provide for the free passage of pressure fluid through the chambers 35d and 34p, ample clearance for this purpose being allowed between valve shank 38b and the opening through split bushing 37.

External grooves 35b are provided around valve lifter piston 35 for the purpose of increasing the

resistance to pressure fluid passing upward between member 35 and nipple 33, and to provide lodgement space for foreign substances that might otherwise impair free movement of the member.

Internal grooves 29a and 40b are to house a lubricant such as a mixture of graphite and cup grease, for the purpose of lubricating the valve 34a. It will be noted that once these grooves are packed with a lubricant such as mentioned, the lubricant cannot readily escape on account of the closure produced by the valve, and will remain in place for a considerable time. Lower extension 34b, while no part of the valve proper, serves to cover the grease filled grooves 40b, as appears in Fig. 3, when the valve is in its upper position, intaking well liquid through the open shell section 34d, then in registration with opening 40' having communication with the well liquid as will be explained. This lower extension 34b also preserves the perfect alignment of the valve with its lower female member 40, when the valve 34a is wholly within the member 29. Except for this extension 34b, the valve 34a might land and hang upon the upper end of member 40 when the valve seeks to return to its position shown in Fig. 2 if, through imperfect workmanship, the alignment between the central openings through members 29 and 40 should be untrue.

The construction shown in Figs. 2 and 3, as above described, will now be shown installed in a well opposite the bracketed space A by means of a reducer 21 connecting the upper end of nipple 28 to the lower end of eduction tube 3, commonly called the flow tubing. Lead seal 25b, integral with the member 25, engages upon landing seat swage 14 to produce a hermetic seal between the flow tubing 3 and the pressure tubing 2. In this position extension 25c forces valve 24 from its seat 14a, upon which the valve engages whenever the flow tubing is not in place. The spring 23 within nipple 15, resting upon annular plate 17 in coupling 16, is of sufficient force to cause such engagement. Valve 24 serves to prevent well liquid from entering the pressure tubing at all times when the flow tubing is not in place. Swaged nipple 18, coupling 19, and perforated landing joint 20, closed at its lower end by cap 21, resting upon bottom of the well B, illustrate other proper parts and fittings such as should ordinarily be installed below the device.

In Fig. 1 it will be noted that the upper end of well casing 1, casing head, composed of base 4, closed on one side by pull plug 4a, cap 5, plate 6, seal ring 7, coupling 8, and weld 8a, are arranged to provide means for a hermetic seal between the well casing and pressure tubing 2 proximately above ground line G. It will also be observed that nipple 9, has an internal annular plate section 9a supporting coupling 10 upon packing 11. Packing gland 12, and packing 13, likewise provide means for producing a hermetic seal between pressure tubing 2 and flow tubing 3. The swaged nipples 26 and 26a may be used to expand the annular space S' in order to provide storage for ample pressure fluid within the well that the slugs may be expelled without drawing heavily upon the pressure fluid supplied through pipe line 9c.

None of the parts, nor their arrangement, described in the two preceding paragraphs are new; but the same are necessary to properly install and show the device illustrated in Figs. 2, 3, 4 and 5, which I claim is new.

It is understood that the upper end of flow line 3 leads to a tank. Surplus gas produced by the well may be conducted away by line 4b. Air or gas for flowing the well may be supplied from an external source through a pipe line 9c connected to extension 9b; or if the well produces enough gas to flow it, gas from the annular space S may be conducted into the annular space S' by means of a tubular connection that can be easily made between nipple 4b and extension 9b.

Operation of the device shown in Figs. 2 and 3 as installed in Fig. 1 will now be explained.

It should be noted that the circular enlarged portion 36a of valve 36 has impaired clearance around it which should vary directly with the size of the flow tubing. Around this enlarged portion 36a, and through the slight clearance between valve lifter piston 35 and nipple 39, all the pressure fluid required to expel the slug must flow.

The well will be assumed to be standing with liquid in the annular space S at the level L. Well liquid enters the well casing or liner through perforations P communicating with the producing formations. This liquid is kept out of the flow tubing 3, for the time being by valve 34a which closes opening 40' as appears in Fig. 2.

Compressed air or gas will now be admitted into the annular space S' within the pressure tubing through input line or nipple 9c, it being borne in mind that tubular member 9c may receive its pressure fluid from an external source such as a compressor or a gas line; or 9c may be a nipple having connection with the nipple 4b through which gas from the well itself in the annular space S may be admitted into the annular space S'.

Pressure fluid so admitted enters intake ports 31a and passage 31b and lifts check valve 38 from its seat 31e with a few ounces of pressure. The pressure fluid stream then divides, part going around head 38a, through chamber 36c, passage 36d, and out through openings between fins at upper end of passage 36d. The other part passes around tubular lower end 36c and unites with the first stream between fins 36b. Thence, the pressure fluid stream again divides, part passing between legs 35a and around piston 35. The other part passes around enlargement 36a, through chambers 35d and 34p, passage 34j, and radial openings 34f, both streams again uniting in the chamber containing valve member 34. Thence the pressure fluid flows through the passages 34m between ribs 34c (Fig. 7), passes weight 41, and enters the flow tubing 3.

At a predetermined velocity the pressure fluid, flowing through the path indicated in the preceding paragraph, due to resistance offered by the enlarged portion 36a will raise and seat valve 36, preferably weighing 2-5 pounds, upon seat 34h. Seating of valve 36 forces all of the pressure fluid to pass between valve lifter piston 35 and nipple 39, at which time grooves 35b offer greatly increased resistance to such passage. The added resistance resulting from this closing of one of the pressure fluid paths quickly closes the other by causing valve 34 to engage upon valve seat 40c, as shown in Fig. 3. Seating this valve wholly stops the escape of pressure fluid into the flow tubing. At the same time well liquid is admitted into the flow tubing by bringing openings 34d

and 40' into registration as appears in Figs. 3 and 5.

The path of the well liquid from the annular space S into the flow tubing is via perforations 20a, joint 20, nipple 18, opening through plate 17, nipple 15, perforations 25a, extension 25c, check valve 32 (free to be opened by pressure from below), cored passages 31d (Figs. 2, 4, 5, and 10), outermost annular passage within nipple 30, openings 40' and 34d, which last two mentioned openings are now in registration (see Figs. 3 and 5), openings 34m between ribs 34c, and opening around weight 41 within nipples 28 and 29.

15 Valve 34 being seated as in Fig. 3, well liquid in the flow tubing exerts a back pressure upon the valve surface 34e. When enough well liquid has entered the flow tubing to balance the pressure fluid force in annular space S', with aid of 20 weight 41, the forces seating and tending to unseat valve 34 become equal. Well liquid will continue to flow into the flow tubing until the unseating force (the weight of well liquid in flow tubing, plus weight 41), is great enough to unseat valve 34.

25 When valve 34 is unseated by the back pressure of well liquid in the flow tubing, aided by the force of weight 41 as stated, the entire movable assembly quickly returns from the position shown in Fig. 3 to the position shown in Fig. 2, in which position the pressure fluid follows the path hereinbefore stated and expels the slug of well liquid from the flow tubing.

30 Attention should be called to the fact that the back pressure which opens valve 34 is greatly increased immediately after the valve opens by the added force of the pressure fluid contacting the inert slug. This added back pressure causes the movable assembly to return instantly to the position shown in Fig. 2 after valve 34 opens.

35 When the slug of well liquid begins to leave the flow tubing, the expansion of the pressure fluid under the slug becomes progressively more rapid due to the constantly lightening load. The velocity of pressure fluid entering through the movable assembly, therefore, rapidly increases and soon again causes valves 36 and 34 to seat, thereby cutting off the entrance of pressure fluid into the flow tubing and at the same time admitting well liquid into the flow tubing through the resulting registration of openings 34d and 40' as before described. This cycle automatically repeats under the conditions stated.

40 55 To demonstrate, by example, the cycle as herein explained, the following is assumed:

1. The liquid level L in the space S is standing at 1000 feet above the device.

2. Each 100 feet of the liquid column exerts a pressure of 40 pounds per square inch at the level of the device.

3. Weight 41 weighs 50 pounds.

4. The area 34e of valve 34, exposed to back pressure in the flow tubing, equals one square inch.

5. The air or gas pressure in line 9c is 200 pounds per square inch.

6. Ten pounds per square inch is the force required to overcome valve friction.

70 The pressure fluid at 200 pounds per square inch, as assumed, is turned into the annular space S'. Check valve 38 is almost instantly raised. Valve 36 closes quickly and valve 34 seats soon thereafter raising opening 34d to register with opening 40'. Well liquid rushes

into the flow tubing through openings 40' and 34d as explained. When the flow tubing has filled 400 feet above valve 34, the back pressure on this valve will be 210 pounds per square inch ($4 \times 40 + 50$), or exactly enough to open valve 34 and return the movable assembly to the position shown in Fig. 2.

Pressure fluid at 200 pounds per square inch is thereby discharged into the flow tubing under a liquid load of 160 pounds per square inch which will, of course, quickly expel the slug.

It will be noted in the preceding example that weight 41, weighing 50 pounds, will be raised by 7 1/2 pounds per square inch of lifting force exerted upon valve lifter piston 35 if the cross sectional area of this member is 7 square inches. Such area is permissible within the limits of ordinary well equipment, and a differential of 7 to 10 pounds between the pressures above and below lifter 35 is readily obtainable by providing slight clearance between members 35 and 39. .015" to .025" clearance all around between these members has been found satisfactorily workable. Likewise .015" to .040" clearance between the members 35 and 36a has been found by experience to be workable for sizes approximately 1 1/2 to 3 times larger than the scale shown in Figs. 2, 3, 4, and 5, it being understood that the proportion between the size of device and flow tubing shown should preferably be approximately maintained.

It will be noted from the foregoing example that the length or weight of the slug can be varied by simply varying the value of the pressure fluid, and that the weight of the slug varies directly with said pressure, and that the weight of member 41 determines the difference between the weight of the slug and the pressure of the lifting force.

Weight 41 should preferably be of cast iron, brass, or other metal of great specific gravity in order that it may be comparatively short, 2-4 feet being suitable length.

It should be observed that while valves 34 and 36 are in the lower position, pressure fluid to expel the slug will flow freely around the expanded portion 36a and around piston 35, and that valve 36 should be of such weight and diameter as to not allow it to seat while the slug remains in the flow tubing. When the slug is expelled from the flow tubing, the decreased resistance in the flow tubing causes a rush of pressure fluid past the expanded portion 36a. The resulting resistance seats valve 36. This causes the entire pressure fluid flow to seek passage around valve lifter piston 35 which, due to the slight clearance around it, causes it to act like a piston because, as the velocity increases, the lifting force multiplies approximately according to the square of the velocity.

Check valve 38, which in the lower position of the movable assembly, landing upon its seat 31e, serves to prevent the escape of well liquid into the pressure tubing space S' if any liquid should leak past the valve 34a while the well is standing, as is apparent in Fig. 2. Provision is made to lift this valve with valve 36, as has been explained. This is done because if for any reason valves 34 and 34a should become stuck anywhere above their lower position, pressure may be applied in the flow tubing from the upper end thereof to force these valves downward and free them. Unless check valve 38 were lifted off its seat 31e above passage 31b, it would cause the pressure applied into the flow tubing to equalize

on both sides of the movable assembly, and thus prevent freeing the valves by pressure so applied.

It will furthermore be noted that the height of the liquid column in the annular space S does not affect the operation of the device because valve 34a does not open or close with or against the liquid pressure.

A modified form of this invention is shown in Figs. 4 and 5. The construction of this modification is so similar to the preferred form shown in Figs. 2 and 3 that the description of the modification will be brief.

All parts bearing the same reference characters as in Figs. 2 and 3, in addition to being identical in construction, are also identical in use and purpose, as was explained for the preferred form.

Valve lifter member 35A contains the head 43a of check valve 43 movably engaged upon internal shoulder 35c in order that the check valve will be lifted from its seat 31e above passage 31b when valve 34A rises responsive to the same force that lifts valve 36 in Figs. 2 and 3. Radial openings 35Aa provide fluid circulation in order that the check valve will remain free.

Sleeve nipple 29A and sleeve valve 40A are identical in purpose with parts 29 and 40 respectively in Figs. 2 and 3, and are identical in construction except grooves 29a and 40b used to contain a valve lubricant in Figs. 2 and 3 are not employed in this construction. Some wells which produce clean oil do not require such lubrication. Double valve member 34A, having solid lower threaded extension 34Ag, employs neither radial openings 34f, valve seat 34h, nor vertical passages 34j, as used in valve 34, Figs. 2 and 3, because valve 36 and its lower extension, shown in Figs. 2 and 3, are not here used.

In this modified construction a spring 44 seats upon the finned support 42 and is held under some compression (30 to 60 pounds being workable) by engaging its upper end upon the reducer 21. This spring serves the same purpose as was explained for weight 41 in Figs. 2 and 3. The pointed lower end of spring support 42 engages within the cupped upper extension 34k. The upper end has a free working fit within nipple 28. In some wells which produce a considerable quantity of sand or other solids, a spring such as shown at 44 may be found more practicable than a weight.

It will be understood that the foregoing drawings and specification are illustrative and not intended to limit the construction or uses of this invention which may be greatly varied within the intended scope and purpose thereof.

I claim:

1. In a device of the class described, an eduction tube, a tubular valve housing attached thereto, spaced annular walls in said housing to provide an annular passage longitudinally of the housing to conduct liquids from the lower end of the valve housing into the eduction tube, an opening leading from said passage to the interior of the housing, a sleeve valve within the housing, said valve having an opening adapted to be brought into mating relation with the first mentioned opening, means normally holding the sleeve valve in closed position, and pressure responsive means below the sleeve valve for moving the valve to open position.

2. In a device of the class described, a valve assembly comprising a tubular housing having a central bore of reduced cross section at the upper end thereof, a valve seat at the lower end

of said reduced section, passages in the walls of the housing and having openings to the bore above the valve seat, said passage being adapted to conduct fluid from the lower end of the housing to the upper end of the bore in the housing, a sleeve valve slidable within the reduced section, a piston loosely slid able in the bore below said sleeve valve and having a surface adapted to make sealing engagement with the valve seat and close the bore when the valve sleeve is moved to open position, and means for admitting a pressure fluid below the piston to flow about the piston and through the bore from below the ports and to control the position of the piston.

3. In a fluid lift device, an eduction tube, a valve assembly attached thereto and including a housing, a central bore therein, passages in the walls of said housing to admit liquid longitudinally thereof, said passages terminating in ports interiorly of the housing adjacent the upper end thereof, a sleeve valve within the housing, means normally holding said valve in closed position, pressure means for moving the valve to open position, said pressure means including a second valve member adapted to close the bore below the ports when the sleeve valve is open, and while liquid is admitted through the passages to the eduction tube, and means for admitting a pressure fluid to the bore below said last mentioned means to control the position of said second valve member.

4. In combination, a valve housing having a central bore therein, a passage in the wall of the housing and longitudinally from the lower end thereof, said passage terminating in an interior port adjacent the upper end of the housing, a valve within the housing to move downwardly and close the port, means normally holding said valve in closed position, a valve lifter piston attached to said valve and fitting loosely within the bore to form a restricted passage in the bore below the valve, and means for admitting pressure fluid below said piston to lift the piston and valve and admit fluid through the first mentioned passage to said port.

5. In combination, a valve housing having a central bore reduced at its upper end, a passage in the wall of the housing from the lower end thereof and terminating in a port in the reduced portion of the bore, a sleeve valve adapted to move in the reduced portion to close said port, and lubricant containing grooves in the housing walls adjacent the port.

6. In combination, a valve housing having an axial bore, a by-pass passage from the lower end of the housing and terminating in a port opening into said bore adjacent the upper end thereof, a sleeve valve, means normally holding the sleeve valve to cover said port, a valve lifter piston fitting loosely within said bore below the sleeve valve and connected thereto, and means for applying a gaseous fluid under pressure to the nether side of said piston to lift the piston and open the valve, said valve lifter piston having peripheral grooves whereby the lifting force of the gaseous fluid by passing the piston is increased.

7. In combination, a housing having a central bore and a by-pass passage in the walls thereof, a valve within the housing, means normally urging said valve downwardly to close the by-pass passage, a valve lifter piston fitting loosely within the housing and connected to said valve, a passage through said piston, means for admitting a pressure fluid to the central bore below

the piston, valve means within said piston and adapted to close said passage upon a predetermined velocity of pressure fluid therethrough, so that the pressure fluid is restricted to flow about the piston whereby the movement of the piston and associated valve is accelerated.

8. In a fluid lift device for wells, an eduction tube having an extension upon the lower end thereof, inlet ports in said extension adapted to admit well fluid to said eduction tube, a check valve within and proximate the lower end of said eduction tube, an inlet member in said eduction tube proximately above said check valve, said member having a transverse inlet opening for pressure fluid and an axial passage communicating with and extending upward from said inlet opening, a valve seat around the upper end of said passage and an axial opening extending upward from said seat, a sleeve surrounding the upper end of said inlet member, a tubular valve housing upon the upper end of said sleeve and having within it a downwardly facing valve seat, longitudinal openings for well fluid in said inlet member, said openings by-passing said transverse opening for pressure fluid, an annular valve seat within the lower end of said valve housing, there being an annular space between said eduction tube and said valve housing, another tubular valve housing within said eduction tube in spaced relation to said first valve housing, such relation forming a radial opening communicating between the interior of said valve housings and said by-pass openings for well fluid through said annular space, a loosely fitting piston within said sleeve, said piston having legs normally engaging the upper end of said inlet member and an axial opening having restrictions proximate the upper and lower ends thereof, a valve seat formed within and at the extreme end of said upper restriction and an axial opening communicating with cross bores proximately above said seat, a poppet valve formed upon a reduced portion of said piston proximate the upper end thereof and a sleeve valve upward extension of said poppet valve, said sleeve valve being slid able within said tubular valve housings and adapted to close said radial opening when said piston is engaged upon said inlet member and to open said radial opening when said poppet valve is engaged upon the downwardly facing seat in said first valve housing, means normally urging said sleeve valve downwardly, longitudinal openings through said sleeve valve for pressure fluid passing upward around said piston when said poppet valve is open and for well fluid from said radial opening when said sleeve valve is open, a pressure fluid secondary control valve within said piston for closing said axial opening thereof and diverting the pressure fluid around said piston to hasten the closing of said poppet valve, a depending shell on said secondary control valve and a check valve having a head within said shell and adapted to engage said first mentioned valve seat when no pressure fluid is supplied to the transverse inlet opening.

9. In a differential fluid lift device for wells, an eduction tube having an extension upon the lower end thereof, inlet ports in said extension adapted to admit well fluid to said eduction tube, a check valve within and proximate the lower end of said eduction tube, an inlet member in said eduction tube proximately above said check valve, said member having a transverse opening for pressure fluid communicating with and extending upward from said inlet opening, a valve

seat around the upper end of said passage and an axial opening extending upward from said seat, a sleeve surrounding the upper end of said inlet member a tubular valve housing upon the upper end of said sleeve and having within it a downwardly facing valve seat, longitudinal openings for well fluid in said inlet member, said openings by-passing said transverse opening for pressure fluid, an annular valve seat within the lower end of said valve housing, there being an annular space between said eduction tube and said sleeve and valve housing, another tubular valve housing within said eduction tube in spaced relation to said first valve housing, such relation forming a radial opening communicating between the interior of said valve housings and said by-pass openings for well fluid through said annular space, a loosely fitting piston within said sleeve, said piston having legs normally engaging the upper end of said inlet member, a poppet valve formed upon a reduced portion of said piston proximate the upper end thereof and a sleeve valve extension upward of said poppet valve, said

5 sleeve valve being slidable within said tubular valve housings and adapted to close said radial opening between them when said piston is engaged upon said inlet member, an annular member secured in said eduction tube, a spring support having clearance around it within said eduction tube and being engaged with the upper end of said sleeve valve, a spring between said annular member and said sleeve valve, said spring being adapted to provide the operating differential between the well fluid in said eduction tube and the pressure fluid in said first annular space, longitudinal openings through said sleeve valve for pressure fluid passing upward around said 10 piston when said poppet valve is open and for well fluid from said radial opening when said sleeve valve is open, a check valve having a head loosely secured within said piston, said check valve normally closing said axial passage to prevent well fluid from escaping through the opening in the inlet member tube into the annular space.
